NON-METALLIC MINE FUSE

Fabrizio Lazari, Milan, Italy, assignor to Montecatini, Società Generale per l'Industria Mineraria e Chimica, a corporation of Italy

Application July 17, 1952, Serial No. 299,305

Claims priority, application Italy August 4, 1951

12 Claims. (Cl. 102—70)

This invention relates to a fuze, particularly a non-metallic fuze.

It is known that the fuses of antitank and antipersonnel land mines are usually actuated directly by crushing caused by the weight of the object against which the mines are directed.

These fuses activated by crushing, consist essentially of a percussion cap or detonator which is struck by a firing pin when the fuze is subjected to a predetermined force.

Generally, the striker is projected against the sensitive detonator by the force of a spring, previously compressed and held in such condition by a stop system which is rendered ineffective by crushing the cover of the fuze. In this type of fuze, the release of the spring imparts to the striker a uniform striking force which is always sufficient to insure firing of the detonator.

On the contrary, in other types of fuses the striker is pushed against the detonator directly by the impact exerted upon the cover of the fuze, and in this case, according to the circumstances, the force of the impact may or may not be sufficient to ignite the detonator. The last mentioned type of fuze is particularly adapted for use in non-metallic mines, wherein metallic springs cannot be used.

It is therefore an object of the present invention to provide a wholly non-magnetic fuze, which comprises a detonator, a striker for igniting said detonator and which includes a device to insure that the striker is actuated by a constant force of impact, independent of the direction in which the force crushing the cover is applied.

In particular this effect is attained in the present invention by replacing the predetermined elastic force of a spring by the elastic force of a compressed gas contained in a hermetically sealed container. The gas container is disposed in a chamber at one end of which the striker is slidably fitted as a piston. Breakage of the compressed gas container, upon crushing of the fuze, exerts a pressure upon the striker and projects it against a suitably located percussion cap, striking it with a uniform force always sufficient to ignite the detonator. The gas container may consist of a vitreous or glass ampoule, which in addition to the required fragility offers an unexpected high resistance to the internal pressure, in comparison with the necessarily small thickness of the walls. The gas container is preferably charged with a stable gas under a pressure of from 1 to 30 atmospheres. Methods of making gas containers suitable for use in the non-metallic land mine herein disclosed are described in applicant's copending application titled: Process for Filling and Treating Pressure Capsules for use in Non-Metallic Fuzes, Serial No. 612,177, filed September 26, 1956.

For further details of the invention reference is made to the following description and drawing, which are intended to be illustrative and not limitative, of an embodiment of a fuze according to the present invention.

2

The fuze consists of a base 1 and cap or cover 2, made of rigid material, having adequate resistance (e. g. synthetic resin) and of a perimetral band 3 made also from stiff material and having a fragility adequate for the sensitivity required of the fuse. Such a band constitutes at the same time the rigid and hermetic connection of the base with the cover and the predetermined fracture zone when the fuse is crushed by a body of a determined weight.

10 Inside the enclosure composed of the cover 2, the base 1 and the band 3, are two cylindrical coaxial sockets 4 and 4', respectively integral with the cover and secured to the base are surrounded by a plastic material envelope 5. The envelope 5 affords a gas-tight but non-rigid connection between the sockets. Inside the sockets is disposed the compressed gas container 6 made of fragile material (e. g. glass). The container 6 comprises a vitreous or glass ampoule containing a pre-fill of compressed propellant gas.

15 The internal recess, cavity or bore 7 of the socket 4' communicates with the recess or bore in the base of the fuse. Within the bore at a convenient height the striker 8 is located, which operates as a piston. The striker 8 is held in place by a thin and yieldable baffle 9, which serves to preserve the hermetic closure of the pneumatic chamber. Under the striker, the detonating means of percussion cap 10, containing the blasting fuse, is located.

20 When the cover of the fuse is subjected to a weight superior to that for which it was adjusted, the band 3 yields, the cover 2 presses against the container 6 breaking it, and the instantaneous pressure exerted by the compressed gas in the channel 7 propels the firing pin against the detonating cap. Breaking of container 6 is also insured even if the cover, which has an arched or domed form, such as that form of a mushroom, is pressed marginally. It therefore acts on the container as a torsional or twisting couple.

I claim:

40 1. A percussion fuze for non-metallic mines, comprising a percussion cap, a striker for igniting said percussion cap, a frangible hermetically sealed container containing a pre-fill of compressed propellant gas, said striker being disposed in striking position between said container and said percussion cap, and enclosure means surrounding said container and said striker, said enclosure means being operative, upon impact thereupon, to break said frangible container, whereby said striker will be propelled by the kinetic energy of the released gas to strike upon and ignite said percussion cap.

45 2. A percussion fuze for non-metallic mines comprising a percussion cap, a striker for igniting said percussion cap, a frangible hermetically sealed container containing a pre-fill of compressed propellant gas, said

50 striker being disposed in striking position between said container and said percussion cap, and enclosure means surrounding said container and said striker, said enclosure means being operative, upon impact thereupon,

55 to break said frangible container, whereby said striker will be propelled by the kinetic energy of the released gas to strike upon and ignite said percussion cap, said enclosure means comprising a base member and a cap member,

60 means for holding said base and cap members in spaced relation, a first recess in said base member, said striker being slidably disposed in said first bore,

65 a second recess in said cap member, said container being disposed in embracing relationship within said first and second recesses and intermediate said base and cap members.

70 3. The invention as defined in claim 2 including frangi-

ble baffle means for sealing said striker in said first bore prior to fracture of said frangible container.

4. The invention as defined in claim 2 wherein said base and said cap are provided with coaxial cylindrical surfaces, and including a stiff, cylindrical band fixed between said surfaces to hold said base and cap in spaced coaxial alignment, said band being of predetermined fragility whereby an impact of certain force will distort it and allow the base and cap to be moved relative each other to fracture the gas container.

5. The invention as defined in claim 2 wherein said holding and enclosure means comprises a resilient cylindrical sleeve, and a pair of complementary coaxial cylindrical shoulders surrounding said first and second bores, said sleeve being hermetically sealed against said shoulders.

6. The invention as defined in claim 2 wherein said cap is arched upwardly, whereby impacts upon the side thereof will result in forces acting as a torsion couple upon said gas container.

7. A springless non-metallic percussion fuze for land mines comprising a percussion cap, a firing striker for the percussion cap, a frangible hermetically sealed container containing a pre-fill of compressed propellant gas, the striker being positioned between said container and the percussion cap, enclosure means surrounding said sealed container and said striker, said enclosure means providing a base, an impact cap, and a lateral gas retaining wall connecting the base and impact cap, impact upon the cap serving to break the frangible container to release the compressed gas, the released gas being confined within the enclosure means and against the striker, whereby the striker is propelled by the force of the gas to strike upon the percussion cap, the gas imparting to the striker a kinetic energy sufficient for ignition.

8. The apparatus defined in claim 7, the impact cap having an outer surface which is arched at its periphery, to augment twisting and breaking action on the sealed container imparted by a laterally directed impact force.

9. A non-metallic percussion fuze for land mines comprising: a percussion cap; a firing striker for the percussion cap; a frangible hermetically sealed vitreous ampule containing compressed gas; the striker being positioned between said ampule and the percussion cap; enclosure means surrounding said ampule and said striker, said enclosure means providing a base structure having a recess, an impact cap having a recess, and a lateral gas retaining wall; the ampule extending into said recesses, impact upon the cap serving to apply breaking force to the frangible container to release the compressed gas, the released gas being confined within the enclosure means to act against the striker, whereby the striker is propelled by the gas to strike upon the percussion cap.

10. A non-metallic percussion fuze for land mines comprising: a percussion cap; a firing striker means for the percussion cap including a gas-propelled piston; a frangible hermetically sealed container containing a propellant consisting of compressed gas; the striker means being positioned between said container and the percussion cap; enclosure means surrounding said sealed container and said striker means; said enclosure means providing a base, an impact cap, and a lateral wall con-

necting the base and impact cap, impact upon the cap serving to apply breaking force to the frangible container to release the compressed gas, the released gas being confined within the enclosure means and against the piston of striker means, whereby the striker means is propelled to strike upon the percussion cap.

11. A springless non-metallic percussion fuze for land mines comprising a percussion cap, a firing striker means for the percussion cap, said striker means including a gas-propellable piston; a frangible hermetically sealed container containing compressed gas, the striker means being positioned between said container and the percussion cap; enclosure means surrounding said sealed container and said striker means, said enclosure means providing a base structure carrying the percussion cap, an impact cap, and a lateral wall connecting the cap and base structure; the impact cap being spaced from the base structure by said wall, the cap and base structure each having recesses, the sealed container extending into said recesses, the piston of the striker means being positioned in the recess of the base structure, the lateral wall yielding upon impact applied to the impact cap, impact upon the cap serving to apply breaking force to the frangible container to release the compressed gas, the released gas being confined within the enclosure means and against the piston of the striker means, whereby the striker means is propelled to strike upon the percussion cap.

12. A non-metallic percussion fuze for land mines comprising a percussion cap, a firing striker for the percussion cap, a frangible hermetically sealed container containing a pre-fill of compressed propellant gas, the striker being positioned between said container and the percussion cap, enclosure means surrounding said sealed container and said striker, said enclosure means providing a base structure carrying the percussion cap, an impact cap, and a lateral distortable sealing band connecting the base structure and the impact cap in spaced relation, impact upon the cap serving to distort the band and permit the movement of the impact cap with respect to the base structure, to apply breaking force to the frangible container to release the compressed gas, the released gas being confined within the enclosure means and acting against the striker, whereby the striker is propelled by the force of the gas to strike upon the percussion cap.
